UNITED STATES PATENT OFFICE.

ROBERT F. STUART, OF KOKOMO, INDIANA.

BOX-MARKING MACHINE.

1,351,353.

Specification of Letters Patent. Patented Aug. 31, 1920.

Application filed December 19, 1918. Serial No. 267,422.

To all whom it may concern:

Be it known that I, ROBERT F. STUART, citizen of the United States, residing in the city of Kokomo, Howard county, Indiana, have invented certain new and useful Improvements in Box-Marking Machines; and I do hereby declare the following to be a full, clear, and exact description of the invention, such as will enable others skilled in the art to which it appertains to make and use the same.

My invention relates to a machine for marking boxes or other packages; that is to say, for printing addresses and the like directly upon such objects instead of applying these inscriptions by hand or through stencils. In its general objects, my invention aims to provide a comparatively simple and easily operable machine of this class in which each of the imprinting elements will be automatically retracted after each has performed its work, in which each imprinting element will vary in its effective travel according to the surface encountered by it and will thereby automatically adjust itself to irregularities in its service; in which the package will automatically be advanced a distance corresponding to a single space between the actuating of the imprinting elements; in which such spacing also can readily be effected without moving any imprinting element, thereby permitting of added spacing when desired; in which the box can readily be raised or lowered to vary the lines along which the imprinting is effected, and in which the imprinting elements will automatically be inked during the operation of the machine.

More particularly, my invention aims to provide a machine of this class in which the imprinting elements are carried by a rotatably mounted drum, and in which the position of the operatively located imprinting element will readily be disclosed by a visual indicator; to provide simple and foot-operated means for actuating the particular imprinting element which is disposed in operative position; to provide means for accurately alining the desired element with the actuating means; and to provide automatic means for retracting both the imprinting element and the actuating mechanism after the actuating of each imprinting element. Furthermore, my invention aims to provide simple means for successively moving the box in one direction between the imprinting

of different elements, and to provide simple and separate means for moving the box in a relatively transverse direction without interfering with the aforesaid successive moving of the box in the other direction. My invention also aims to provide a simple mechanism portion so arranged that when moved part way, it will shift the position of the box in one direction corresponding to the proposed spacing of the imprinting letters for figures, and that when the mechanism is moved farther it will effect the imprinting of some one of the imprinting elements. For this latter purpose, my invention desirably aims to provide a carriage supporting the package and to provide means for moving the carriage, including a ratchet, a dog arranged for rotating the ratchet a desired distance, and means for operatively disconnecting the dog from the ratchet wheel after it has effected this desired movement; also, to provide simple means for accurately adjusting this desired movement of the ratchet wheel, and simple means for insuring a returning of the dog to its operative position.

Still further and to some extent more detailed objects will appear from the following specification and from the accompanying drawings, in which drawings—

Figure 1 is a front view of a machine embodying my invention, with the cover plate cut away to expose a part of the drum and of the type-imprinting elements.

Fig. 2 is a central and vertical transverse section through Fig. 1.

Fig. 3 is a horizontal section of the same machine, taken from the line 3—3 of Fig. 2.

Fig. 4 is an enlarged and vertical section taken along the center line of the operatively disposed imprinting element and showing the arrangements for alining and actuating this element.

Fig. 5 is a detail view showing the ratchet arrangement for actuating the lateral advancing of the carriage which supports the box or other package.

Fig. 6 is a side elevation of some of the same parts of Fig. 5 taken from the line 6—6 of the latter.

In the embodiment of the drawings, the machine of my invention has a frame including legs 1 supporting a table 2 and connected at some distance below the said table by cross bars 3, which cross bars form bearings for certain parts of the mechanism.

Mounted upon the table 2 is a frame 4 supporting a horizontal shaft 5 which forms a bearing for a drum 6. This drum has a substantially channel-sectioned rim 7 equipped with bores extending parallel to the shaft of the drum and spaced at uniform distances from each other. Each of these bores houses a plunger 8 which is normally pressed in one direction by a spring 9 (as shown in Fig. 4) and which has its rear face equipped with a type element 10. The hub of the drum has fast upon it a pointer 11 moving over a dial 12 disposed in front of the drum and marked in letters and figures corresponding to those carried by the type-carrying plungers or imprinting elements. Each of these latter elements is kept from rotating in the bore in which it is mounted, by suitable means, such as a pin 13 fast in one of the channel webs 20 of the drum and extending into a corresponding groove disposed in the adjacent plunger and extending longitudinally of the latter as shown in Fig. 4.

In front of the rear end of one of the said plungers, and desirably in front of the lowermost plunger, I dispose a striker 14, mounted on a slide 15 which is carried by a base 16 fastened to a table top 2 and so arranged that this slide may be moved back and forth in a direction parallel to the axis of the adjacent plunger 8. The slide 15 desirably carries a rack 17 meshing with a segmental gear 18, thus affording substantially a bell-crank connection whereby the slide 30 may be moved back and forth by partially rotating the segment 18 in opposite directions. For this latter purpose, I desirably provide a link 19 having a slotted end adapted to engage a pin 20 on an arm carried by the segmental gear 18. This link 19 extends vertically through an opening in the table top 2 and is connected at its lower end to a foot lever 21 carrying a treadle 22, the foot lever being normally kept in its most elevated position by a spring 23 and a suitable connection 24 interposed between the lever 21 and the table top 2, as shown in Fig. 2. With the parts thus disposed, it will be obvious that in raising the foot lever 21, the spring 23 will also raise the link 19, thus causing the lower end of the slotted opening in the latter to engage the pin 20 so as to hold the slide 15 in its retracted position of Fig. 4. On depressing the treadle, the link 19 will first move without affecting the position of the segment 18 or the slide 15; but as soon as the upper end of the loop 43 forming the head of this link 19 strikes the pin 20, the segment 18 will be partially rotated, thereby moving the slide 15 and causing the striker 14 to force the plunger 8 rearwardly of the machine against the pressure of the spring 9. To insure the reasonably accurate alining of this striker 14 with one of the type-carrying plungers which is

to be actuated, I provide suitable means for preventing the striker from being actuated when the parts are not in their desired alinement. For example, I may equip the forward channel web of the drum with substantially semicircular notches as shown in detail in Fig. 4, and may mount upon the slide 15 a finger 25 adapted to enter one of these notches freely when the adjacent plunger is in alinement with the striker 14. The guide finger 25 desirably has a tapering tip, as shown in Fig. 4, so that it will automatically rotate the drum slightly in case the initial alinement into which the drum was moved by hand was not adequate. This moving of the drum is desirably effected by means of a ring shaped handle 26, which may be disposed as shown in Figs. 1 and 2.

To support the box or other package which is to be imprinted, I provide a carriage including a wheeled base 28 upon which the box is supported and which carries clamping jaws 29 between which the box may be clamped, the rear jaw being desirably high enough to brace the back of the box against the strain of the imprinting. The wheels of this carriage travel on rails 30 mounted on the head 31 of a plunger 32, which plunger is vertically slidable in a column 33 disposed behind the frame 1. The column 33 is desirably slotted at one side and the plunger 32 has a web projecting through this vertical slot and carrying a rack 34 in engagement with a pinion 35. The pinion 35 is fast upon a shaft extending through bearings on the cross bars 3 to the front of the machine, and the forward end of this shaft is fastened to a ratchet wheel 36. This ratchet wheel may be moved by a yieldingly mounted pawl carried by a lever 37, the pawl being releasable through a suitable connection terminating in an auxiliary lever 38. Thus arranged, it will be obvious from Fig. 1 that by swinging the lever 37 back and forth, the ratchet wheel 36 will cause the shaft carrying the same to rotate, thereby rotating the pinion 35 and raising the rack 34, the latter being normally kept from moving downward by a suitably arranged pawl 44 which may be released by a foot lever 45. Consequently, the lever 37 readily permits the rails 30 to be raised to any desired height, while a disengaging of the pawl by means of the foot lever 45 will permit gravity to lower the track as much as may be desired.

To move the carriage 28 along the track, I attach one of its axles to cords 37 running over pulleys at one end of the plunger head 31 and each wound around drums 38, which drums are fast on the shaft carrying the ratchet 39 shown in Fig. 1. This ratchet is normally engaged by a dog comprising a tooth on a pawl 40 pivotally connected to the vertical link 19, as shown in Figs. 1

and 2. Consequently, a downward movement of the link 19 as effected by depressing the treadle 22 will rotate the ratchet wheel 39 and the drum fastened to the latter, therefore 5 by correspondingly winding the cord 37 on this drum and moving the carriage 28 of Fig. 1 toward the left, the flexible cord connections permitting a definite movement to be secured regardless of the height of the 10 carriage with respect to the ratchet 39. To limit this movement to a distance corresponding to the successive spacing of the desired type imprints, I desirably proportion the size of the teeth on the ratchet wheel 39 15 to this spacing. Then I provide means for automatically moving the tooth on the pawl 40 out of engagement with this ratchet wheel after the latter has been rotated a distance corresponding to one of its teeth by this 20 pawl. For example, I may provide a trip 41 having an inclined face disposed for engaging the tooth on the pawl 40, this trip 41 desirably being bolted to the cross-bar 3 through a slot in the trip, as shown in Figs. 25 5 and 6, so that the position of the trip may be accurately adjusted to permit just the desired extent of movement of the ratchet wheel 39 by the pawl 40. To prevent this pawl from accidentally being thrown over 30 too far by the momentum of its engagement with the trip 41, I desirably provide a loop 42 fast upon the trip 41 arranged as shown in Fig. 6 for limiting the movement of the pawl 40 away from the ratchet wheel in 35 which it is normally in engagement.

I also desirably proportion the length of the loop 43 at the upper end of the link 19 so that the lost motion afforded by this loop will be approximately that required for 40 moving the pawl 40 through the link 19 to a distance corresponding to the advance of the ratchet wheel 39 by one tooth. Consequently, if the treadle is only depressed sufficiently to bring the upper end of the loop 45 43 into engagement with the pin 20, and if the pressure is then released so that the spring 23 returns the link 19 to its normal position, the result will only be the lateral moving of the carriage, or in other words 50 the movement of the box to correspond to a single space. I can therefore readily move the box laterally for any number of these desired spaces without effecting any imprinting.

55 When any letter or figure is to be imprinted, I rotate the drum 6 by means of the handle 26 until the desired figure is opposite the tip of the pointer 11, which means that the plunger carrying the corresponding 60 type face is opposite the striker 14. Then I depress the foot lever 21 to its full extent, thereby first advancing the box laterally to the extent of one space and then printing the desired type on the forward face of the 65 box. On releasing the pressure on the

treadle, the spring 23 automatically returns the parts to their normal position, retracting the striker as well as the guide pin 25, so that the drum is free to be rotated to bring the next desired type face into operative position. Then the next depressing of the treadle again moves the carriage laterally, corresponding to the desired spacing of the letters, and thereafter imprints the next type face on the box. 70

By clamping the box between the jaws 28, or at least providing a suitably adjusted rear jaw or fence against which the back of the box bears, and holding the front of the box closer to the drum than the limit of 80 rearward travel of the type on the imprinting elements, I enable each plunger automatically to adjust the extent of its movement to irregularities in the thickness of the boards comprising the face of the box, 85 or to other irregularities in the surface of the box, as the operator merely depresses the treadle until the type plunger is firmly stopped by engagement with the box. 90

To supply the type faces on the plungers 90 with ink, I supply some inking arrangement, as for example a roller 46 disposed in the path through which the faces of the type are rotated when the drum is moved, this roller being supplied with ink from a 95 companion roller dipping into an ink font 47, the ink font may be desirably mounted on pivots supported by the frame 4, (as shown in Fig. 1) so that this ink font may be swung out of the way if necessary, to 100 permit imprinting on a box or package to unusual height. However, it is normally disposed so that when the drum 6 is rotated in swinging one after another of the desired letters into position, the type faces will successively pass over the roller 46 and will be 105 inked by the latter.

From the above description it will be obvious that the spacing of the type letters is entirely automatic, although auxiliary spacing may be effected by depressing the foot lever 21 only part of the way. Also, that the rails and consequently the carriage 28 may readily be raised or lowered so as to shift the box in position for imprinting on other desired lines, and that the flexible cords 37 will permit this shifting without appreciably affecting the subsequent spacing of the remainder of the letters. However, while I have illustrated and described the 110 machine of my invention in a certain desirable embodiment, I do not wish to be limited to the details of construction and arrangement here disclosed, it being obvious that the same might be varied in many respects without departing from the spirit of 115 my invention.

I claim as my invention:

1. In a package imprinting machine, 120 printing means, means to move the printing 125 means, means to move the printing 130

means to printing position, package carrier means, means common to the moving means and to the carrier means to actuate each, and means whereby said common means may be continuously operated without effecting actuation of the moving means.

2. In an appliance of the class designated, type-imprinting means, means for holding a package in operative relation to the type-imprinting means, and coöperating means for actuating the type-imprinting means and for moving the package for a predetermined distance in one direction, the said coöperating means including a pawl, a ratchet engaged thereby, a drum fast with respect to the ratchet, a movable carrier for the package, and a flexible cord connected to the carrier and wound around the drum upon rotation of the carrier by the pawl.

20 3. In a package imprinting machine, slideable printing means, a horizontally moving carrier, a pivoted device to slide the printing means, a vertical rod having a lost-motion connection with the pivoted device, and means actuated by the rod to move the carrier horizontally, said lost-motion connection being formed and arranged so that the rod may be actuated to move the carrier without actuating the pivoted device.

30 4. In a package imprinting machine, a bed, a pivoted drum above the bed, a series of tensioned printing plungers slidably carried by the drum, a slide on the bed having a rack, a segmental pivoted gear in mesh 35 with the rack, a striker borne by the slide and engageable with the plungers, a guide finger carried by the slide, the drum having parts engageable with the guide finger, and a vertically depressible member connected 40 to the gear to actuate same.

5. In a package imprinting machine, a pivoted drum, tensioned printing plungers slidably carried by the drum, means to move the plungers to printing position; a package carrier, means to effect horizontal movement of the carrier, and combined foot operated means to actuate the plunger moving means and said carrier moving means to effect predetermined movement of the carrier upon each operation of the plunger moving means.

45 6. In a package imprinting machine, a pivoted drum, tensioned printing plungers slidably carried by the drum, means to move the plungers to printing position, a package carrier, means to effect horizontal movement of the carrier, and means including a vertical, depressible foot operated rod to move the plungers to printing position and 50 to effect predetermined movement of the carrier upon each operation of the member.

7. In a package imprinting machine, a pivoted drum, tensioned printing plungers slidably carried by the drum, means to move 60 the plungers to printing position, a pack-

age carrier, means to effect horizontal movement of the carrier, combined means to actuate the plunger moving means and said carrier moving means to effect predetermined movement of the carrier upon each operation of the plunger moving means, and means whereby said combined means may be continuously moved to actuate the carrier moving means without effecting movement of the plunger moving means.

75 8. In a package imprinting machine, printing means, a horizontally movable package carrier, means to vertically adjust the carrier, and means to move the carrier horizontally including a flexible element connected to the carrier whereby to allow the carrier to be adjusted vertically while maintaining operative connection with the carrier.

80 9. In a package imprinting machine, printing means, a horizontally movable carrier, means to adjust the carrier vertically, driving means for the carrier, and a flexible connection between the driving means and the carrier to allow the latter to be vertically 85 adjusted.

90 10. In a package imprinting machine, printing means, a horizontally movable carrier, and combined means to actuate the printing means and the carrier including 95 lost-motion means whereby the carrier may be actuated without effecting actuation of the printing means.

100 11. In a package imprinting machine, printing means, a horizontally movable carrier, a drum, a flexible connection between the drum and carrier, means to actuate the printing means, means between said actuating means and the drum to operate the latter to wind the flexible connection thereon and move the carrier, and a lost motion connection between the actuating means and the printing means to allow the carrier to be advanced without effecting movement of the printing means.

105 12. In a package imprinting machine, a bed, a pivoted drum above the bed, a series of tensioned printing plungers slidably carried by the drum, a slide on the bed, a rigid striker borne by the slide and engageable 115 with the plungers, a rigid guide finger carried by the slide, the drum having parts engageable with the guide finger, and means to actuate the slide.

110 13. In an imprinting machine, reciprocating printing members, a horizontally moving package carrier, means to effect reciprocation of the printing members, means to move the carrier, a vertical foot operated rod, means actuated by the rod to operate the 120 carrier moving means, and a lost motion connection between the rod and the reciprocating means of the printing members.

125 14. In a package imprinting machine, slideable printing members, a horizontally 130

moving carrier, means to move the carrier, a vertically slidable foot operated rod, means actuated by the rod to slide the printing members, and means operated by the rod 5 to actuate the carrier moving means.

15. In an imprinting machine, printing means, a package carrier, a reciprocal element common to both the printing means

and carrier, means actuated by said element to move the printing means to printing position, and means actuated by the element to move the carrier. 10

Signed at Kokomo, Indiana, December 14, 1918.

ROBERT F. STUART
